By *Napoléon Giard* *Attorneys*

UNITED STATES PATENT OFFICE

NAPOLEON GIARD, OF ROUGEMONT, QUEBEC, CANADA

TABLE

Application filed March 19, 1929. Serial No. 348,255.

The present invention relates to improvements in table construction and has particular reference to tables of the extension type embodying combined rigid and flexible adjustable top portions.

An important object of the invention is the provision of a table of the above character constructed so that the rigid top portion can be adjusted, when the top is retracted, tightly against and in alignment with a fixed top portion of the table.

A further object of the invention is the provision of a table of the above character constructed so that the flexible portion of the top is loosely connected to the rigid portion to enable the inner edge of the rigid top portion to be positioned tightly against a fixed top bar of the table.

Another object of the invention is the provision of an improved table of the above type designed so that the flexible top portion will be durably supported in horizontal alignment with the rigid portion when the top is extended.

Other objects and advantages of the invention will become apparent as the description progresses.

In the accompanying drawings forming a part of this specification and in which like reference characters are employed to designate corresponding parts throughout the same:

Figure 1 is a fragmentary transverse section through a table top construction,

Figure 2 is a similar view with the top adjusted to an extended position,

Figure 3 is a fragmentary transverse section taken on the line 3-3 of Figure 2,

Figure 4 is a similar view taken on the line 4-4 of Figure 2,

Figure 5 is a longitudinal section through a table top showing a modified construction,

Figure 6 is a similar view of the top in a retracted position, and

Figure 7 is a transverse section taken on the line 7-7 of Figure 5.

With particular reference to Figures 1 to 4 inclusive, wherein is illustrated the preferred form of the invention, the numeral 10 generally designates a fixed top bar of the

table, usually extending transversely between the side panels 11. The present invention is applicable to tables having horizontally extensible tops, either including two sections extending from opposed ends of the table, 55 wherein the top bar 10 is disposed in a central transverse position between the extensible top sections, or tables employing a single top section wherein the bar 10 is disposed on one end of the table. 60

The movable top section embodies a rigid portion 12 supported for horizontal sliding movement between the side panels 11. Connected with the rigid portion 12, for adjustable movement, is a flexible portion 13 embodying a series of transversely elongated bars connected in continuous arrangement by means of a pair of flexible strips 14. The strips 14 are extended beyond the bars at one end and are attached to the inner edge 65 portion of the rigid top member 12. The flexible top portion is rollable about a pair of rollers 15 journaled at the sides of the table to support the ends of the bars 13.

Heretofore, the connecting strips 14 have 70 been attached to the rigid top portion 12, right to the inner edge thereof, preventing tight closure between the inner edge of the rigid portion and the stationary table portion 10 and forming an objectionable space 75 therebetween. An essential feature of the present invention, is the connection of the flexible strips 14 with the rigid top portion in such manner as to leave the portion immediately adjacent the outer edge unattached 80 whereby in retracted position the rigid top can be disposed directly against the outer edge of the stationary top member 10. This is effected by undercutting the inner marginal portion of the member 12 to form a 85 horizontal face 16 adjacent the inner edge and an angular surface 17 continuing outwardly therefrom.

The ends of the strips 14 are secured to the rigid member 12 by means of a block 18 90 wedging the strips between its inner surface and the inclined surface 17 and secured in position by screws 19. The inner portion of the block 18 is formed with an inwardly projecting shelf 20 disposed at an upward in- 95

clination. Between the inner edge of the block 18 and the inner edge of the rigid top member 12, the strip 14 is loose so that the bars 13 of the flexible top portion may be rolled about the rollers and permit the inner edge of the rigid portion 12 to move inwardly beyond the centre of the rollers into contact with the outer edge of the fixed bar 10. The intermediate portion of the outer bar 13, 10 adjacent the fixed top portion 12, is supported by means of arms 21 having their inner ends secured to the bar 13 and the outer portions bent in arcuate form and rolled at the outer extremity to move slidably on the 15 shelf 20. Thus, when the top section is arranged in extended position, the arcuate arms 21 will rest on the shelf 20 to support the first top bar 13 between the ends and thus prevent sagging thereof.

20 As shown to advantage in Figures 5 to 7 inclusive, wherein is illustrated a modified form of the invention, the rigid top portion, indicated at 22, is undercut at the inner edge, as indicated at 23. The flexible portion, 25 comprising the transverse bars 24 and flexible securing strips 25, also embodies a fragmentary bar 26 substantially reduced in height with respect to the main bars 24 and formed to fit within the recess formed at the edge of 30 the rigid portion 22. The reduced bar 26 is arranged so that when the top is in contracted position this bar will assume an angular position on the rollers, indicated at 27, to permit the extended upper edge portion to abut 35 the fixed table member 28.

It is to be understood that the form of my invention herein shown and described is to be taken as a preferred example of the same, and that various changes as to the shape, size, 40 and arrangement of parts may be resorted to without departing from the spirit of the invention or the scope of the subjoined claim.

Having thus described my invention, I claim:—

45 In a table top construction including a fixed top bar, a rigid slidable top portion, a flexible top portion having a series of transversely extending bars and a flexible member connecting the bars, said flexible member being formed with an extension at one end, means for connecting the said extension to the rigid top portion inwardly of the inner edge to provide an unattached portion below the margin adjacent the inner edge, and resilient 50 means for supporting the initial bar of the flexible top portion intermediate its ends and flush with the rigid portion when the top is extended.

55 In witness whereof I have hereunto set my hand.

NAPOLEON GIARD.
